(57) **CLAIM**

The ornamental design for an automobile body as shown and described.

DESCRIPTION

FIG. 1 is a front and side perspective view of an automobile body showing our new design;

FIG. 2 is a rear and opposite side perspective view thereof;

FIG. 3 is a side view thereof;

FIG. 4 is an opposite side view thereof;

FIG. 5 is a top plan view thereof;

FIG. 6 is a front view thereof; and,

FIG. 7 is a rear view thereof.

The broken line portions of the automobile body shown throughout the drawing views are for environmental and illustrative purposes that form no part of the claimed design.
